W. C. RANKIN

FASTENER FOR CASEMENT WINDOWS AND SUCH LIKE

Filed Oct. 11, 1922

FIG. 1.

FIG. 2.

Inventor
W.C. Rankin
By Marks Clerk Atty's

UNITED STATES PATENT OFFICE.

WILLIAM CHARLES RANKIN, OF HAMILTON, NEW ZEALAND, ASSIGNOR OF ONE-HALF
TO JOSEPH BIRD, OF HAMILTON, NEW ZEALAND.

FASTENER FOR CASEMENT WINDOWS AND SUCH LIKE.

Application filed October 11, 1922. Serial No. 593,935.

To all whom it may concern:

Be it known that WILLIAM CHARLES RANKIN, a citizen of the British Empire, residing at Main Street, Frankton Junction, town of Hamilton, in the Dominion of New Zealand, has invented certain new and useful Improvements in Fasteners for Casement Windows and such like, of which the following is a specification.

10 This invention relates to fasteners or stays for hinged articles comprising a movable member hinged to a fixed member such as a casement window hinged to a frame. It is hereinafter described in its application to a casement window. The object of the invention is to provide a device adapted to hold in any desired position a casement window with a maximum opening approximating 90 degrees, which opening is much 15 wider than is now possible with the present style of casement stay. By my invention also a window may be locked in a slightly open position to admit of the circulation of air and yet so as to be burglar proof. By 20 my invention also very little space is taken up when the window is closed. The stay as now used which is dropped and placed over a pin is easily accidentally knocked off the pin and is liable to swing and break the 25 window or allows the window to bang open or shut and my invention obviates this defect. The invention consists in the features, 30 combinations and arrangements of parts secured and operating as herein described 35 and more particularly pointed out in the claim.

In the accompanying drawings illustrating the invention Figure 1 is a view showing the device in position where the casement window is closed. Figure 2 is a view showing the device in position when the casement is locked open to its widest extent. Figure 3 is a front elevation of the device. Figure 4 is a plan of the device. 40 Referring to these drawings a bracket or plate (1) is provided with two lugs 7, 7^a and with holes 10 to take fastening screws. A rivet pin 7^b is secured to and between the lugs 7, 7^a and forms the axis pin for one 45 end 2^a of a movable curved arm 2 said end 2^a being drilled to take the pin 7^b. The end 2^a of the arm 2 fits and works between the lugs 7, 7^a. The arm 2 is drilled at intervals 50 with holes 9, 9^a adapted to take a locking pin 4. The drilled holes 9, 9^a (see Figure

4) do not run parallel to either side of the arm 2 nor are they all central of the arm 2 the arm 2 not being in the same working arc as that described by the plates or brackets 1, 3 to which it is attached. The tapered locking pin 4 has a ring top end 4^a for lifting purposes. Another plate or bracket 3 has three lugs 8, 8^a, 8^b, one of which (8) is at the edge of the plate 3, the other two 8^a, 8^b act as guides for the arm 2 between them. There is a rectangular slot 22 in the plate 3 between lugs 8^a and 8^b through which the arm 2 is adapted to slide. A hole 12 is drilled through each of these three lugs at one side thereof and is tapered to 55 take the tapered locking pin 4. A spring 5 surrounds the locking pin 4 and is held between lug 8 and pin 6 which passes through the locking pin. By this spring the tapered pin 4 is kept normally home in 60 the tapered hole 12.

Another set of holes 12^a is drilled through the three lugs near the other side thereof from the other set of holes 12 so that by changing the locking pin 4 from one set 65 of holes 12 to the other 12^a and turning the device upside down it is made attachable to either a left or a right hand swung window. The holes 9, 9^a in the arm 2 are slightly tapered as shown to give a lead 70 for the locking pin. The tapering is done on both sides of the arm for use in the ordinary and the reversed position of the device. Three of these holes 9^a are by preference placed close together so as to afford 75 a small variation of position for the locking pin 4 for locking the window when 80 closed.

In operation a hole 23 of suitable size is bored through the fixed member such as 85 when the device is used on a window 20, through the fixed jamb 15 in a suitable position. The second plate 3 is then secured to the jamb 15 with its bottom edge resting 90 near the sill 16 as shown in Figures 1 and 2 and with the slot 22 over the hole 23 and corresponding therewith and this plate 3 is so situated that the curved arm 2 will pass 95 through the rectangular slot 22 in it and into the hole 23 bored as above mentioned in the jamb 15. The arm 2 is then passed between lugs 8^a and 8^b through slot 22 and 100 into hole 23, then the plate 1 is secured to the hinged member in this case, the bottom rail 14 of the window 20 and when the win- 105

dow 20 is quite closed the end of the arm 2 has moved out of sight behind the jamb 15 through the hole 23 in it. The locking pin 4 is then inserted in one of the holes 9^a 5 and the device is now fixed in working position with the window closed. To open the window the locking pin 4 is pulled up by ring 4^a the window is pushed open to the extent desired and the locking pin is released to enter, under the control of the spring around it, any hole in the arm as desired.

I claim:—

A fastener for casement windows and the like comprising in combination a window frame, a horizontal swinging sash mounted on the frame, a bracket secured to the sash, a curved arm having one end pivoted to the bracket and provided with a series of openings, one side of the sash being provided 15 with a slot for accommodating the inner

portion of the arm when the sash is in a closed position, another bracket provided with a slot and secured to the frame in alignment with the slot therein so that the arm may slide therethrough, a plurality of suitably spaced lugs extending from the last mentioned bracket and provided with pairs of aligning openings and a spring controlled finger operated pin for engagement 25 with either set of aligning apertures in the lugs of the second mentioned bracket and adapted for engagement with the openings in the arm and the openings in the arm being arranged out of parallelism with the 30 sides thereof.

In testimony whereof he has affixed his signature in presence of two witnesses.

WILLIAM CHARLES RANKIN.
